UNITED STATES PATENT OFFICE

166,511

ILLUMINABLE MAKE-UP MIRROR

Ernest H. Westmore, North Hollywood, Calif.

Application September 19, 1949, Serial No. 5,069

Term of patent 3½ years

(Cl. D86—10)

To all whom it may concern:

Be it known that I, Ernest H. Westmore, a British subject, residing at North Hollywood, in the county of Los Angeles and State of California, have invented a new, original, and ornamental Design for an Illuminable Make-Up Mirror, of which the following is a specification, reference being had to the accompanying drawings, forming a part thereof.

Fig. 1 is a perspective view of an illuminable make-up mirror, showing my new design, showing one side which corresponds in appearance with the other side; Fig. 2 is a perspective view of the illuminable make-up mirror showing it in position for use as a stand, and Fig. 3 is a reduced plan view of the illuminable make-up mirror with the parts related as shown in Fig. 2.

I claim:

The ornamental design for an illuminable make-up mirror, as shown and described.

ERNEST H. WESTMORE.
